Attorney

UNITED STATES PATENT OFFICE.

ROSS ALBERT HUGHES, OF MAHNOmen, MINNESOTA.

BULL-PEN-GATE LOCK OR FASTENER.

1,387,401.

Patented Aug. 9, 1921.

Application filed October 5, 1920. Serial No. 414,922.

To all whom it may concern:

Be it known that I, ROSS ALBERT HUGHES, a citizen of the United States, residing at Mahnomen, in the county of Mahnomen and State of Minnesota, have invented certain new and useful Improvements in Bull-Pen-Gate Locks or Fasteners; and I do hereby declare the following to be a full, clear, and exact description of the invention, such as will enable others skilled in the art to which it appertains to make and use the same.

This invention relates to new and useful improvements in gate locks or fasteners for bull pens and has for its primary object the provision of means which will firmly fasten the gate in a closed position and which will prevent said gate from being moved beyond a closed position when moved from an open position to a closed position and will also prevent said gate from being opened inwardly.

Another object of this invention is the provision of a gate lock or fastener of the above stated character which will be simple, durable and efficient, and which may be manufactured and sold at a comparatively low cost.

With these and other objects in view as will become more apparent as the description proceeds, the invention consists in certain novel features of construction, combination, and arrangement of parts as will be hereinafter more fully described and claimed.

For a complete understanding of my invention, reference is to be had to the following description and accompanying drawing, in which:

Figure 1 is a front elevation of a gate lock or fastener constructed in accordance with my invention,

Fig. 2 is a longitudinal sectional view taken on the line 2—2 of Fig. 1,

Fig. 3 is a transverse sectional view taken on the line 3—3 of Fig. 1.

Referring in detail to the drawing, the numeral 1 indicates as an entirety a gate which consists of a substantially rectangular frame 2 constructed from a plurality of pipe sections that are connected by T-couplings 3 and L-couplings 4. Panels 5 constructed from pipes are secured to the T-couplings 3 for closing the frame 2 and one of said panels is omitted and substituted by an actuating member 6 that is rotatably secured to a pair of the T-couplings and has secured thereto a collar 7 on which is formed

oppositely extending ears 8 and 9. The ear 8 has pivoted thereto a handle 10 adapted to be swung downwardly and positioned between a pair of lugs 11 formed on a locking plate 12. The locking plate 12 is secured to a pair of the panels 5 and when the handle 10 is positioned between the lugs, the actuating member 6 is held against rotation.

The gate 1 is mounted for swinging movement about a vertical axis by hinges 13 and some of the panels 5 have secured thereto cuffs 14 on which are formed oppositely extending apertured ears 15 to slidably support locking elements or members 16. The locking elements 16 have their inner ends connected to ears 17 formed on cuffs 18 secured to the actuating member 6 and one of the locking members 16 has its inner end pivotally connected to the ear 9 on the collar 7, thus it will be seen that by swinging the handle 10 when disengaged from between the lugs 11, the locking elements will be extended for engagement with a keeper bar 18 and retracted from engagement with the same when said handle is moved in an opposite direction.

Each of the locking members 16 consists of parallel rods 19 and 20 and the rod 19 is of a greater length than the rod 20 and is disposed on an opposite side of the panel 5 from said rod 20. The rod 20 has one end bent at right angles and formed on the rod 19 as illustrated at 21 to cause said rods to move in unison. The free end of the rod 19 projects beyond the end of the rod 20 for the purpose of always lying in the path of the keeper bar 18 so as to prevent the gate from being moved beyond a closed position when moved from an open position to a closed position and also to prevent said gate from being opened in a reverse direction.

While I have shown and described the preferred embodiment of my invention, it will be understood that minor changes in construction, combination, and arrangement of parts may be made without departing from the spirit and scope of the invention as claimed.

Having thus described the invention what I claim is:

1. A gate fastener including a gate frame, panels carried by said frame, fastening members slidably mounted on said frame for engagement with a keeper, an actuating member journaled to said frame and con-

nected to the fastening members, a handle pivotally connected to the actuating member for rotating the same in either direction, and a fastener carried by the panels and adapted to receive the handle for holding the actuating member against rotation.

2. A gate fastener including a frame having panels, cuffs secured to said panels, apertured ears formed on said cuffs, fastening members slidably mounted in the ears and adapted to engage a keeper when in one position, an actuating member journaled to said frame and pivotally connected to the fastening members, a handle pivoted to the actuating member, a plate secured to a pair of the panels, and spaced lugs formed on said plate and adapted to receive the handle.
3. A gate fastener including a frame hav-

ing panels, actuating members slidably mounted on said frame and each including parallel bars adapted to receive some of the panels between the same and one of said bars being of a greater length than the other bars and one of the bars being formed integrally with the other bar, an actuating member journaled to said frame and pivotally connected to the actuating member, and a handle for rotating the actuating member.

In testimony whereof I affix my signature in presence of two witnesses.

ROSS ALBERT HUGHES.

Witnesses:

CHAS. F. VONDRA,
LEWIS P. WAGNER.
